US00D813760S

(12) **United States Design Patent** (10) **Patent No.:** **US D813,760 S**
Johnson et al. (45) **Date of Patent:** **** Mar. 27, 2018**

(54) **ERGONOMIC PEDAL**

- (71) Applicants: **Paul R. Johnson**, Brentwood, TN (US);
Robert E. Johnson, Hendersonville, TN (US)
- (72) Inventors: **Paul R. Johnson**, Brentwood, TN (US);
Robert E. Johnson, Hendersonville, TN (US)

(73) Assignee: **Johnson Technologies Corporation**,
Nashville, TN (US)

(**) Term: **14 Years**

(21) Appl. No.: **29/474,670**

(22) Filed: **Dec. 22, 2014**

(51) LOC (11) Cl. **12-16**
(52) U.S. Cl. **USPC D12/174**

(57) **CLAIM**

The ornamental design for an ergonomic pedal, as shown and described.

DESCRIPTION

FIG. 1 is a perspective view of an ergonomic pedal showing my new design;

FIG. 2 is a top plan view thereof;

FIG. 3 is a bottom plan view thereof;

FIG. 4 is a front plan view thereof;

FIG. 5 is a back plan view thereof;

FIG. 6 is a left side view thereof; and,

FIG. 7 is a right side view thereof.

The broken lines shown in FIGS. 1 through 7 represent portions of the ergonomic pedal that form no part of the claimed design. The broken lines showing the textured top surface of the ergonomic pedal represents environment and does not form a part of the claimed design.

1 Claim, 3 Drawing Sheets
